CLAIM

The ornamental design for a spiral wound battery, as shown and described.

DESCRIPTION

FIG. 1 is a front perspective view of an embodiment of a battery in accordance with the present invention. The battery includes terminals on the top, curved portions in the front and back, horizontally ribbed portions on the sides, and a rounded, protruding edge portion along the junction between the top of the battery and the main body of the battery. In addition, the battery includes a series of small holes in a horizontal arrangement along a bottom portion of the front and back of the battery.

FIG. 2 is a front view of a battery in accordance with the FIG. 1 embodiment.

FIG. 3 is a top view of a battery in accordance with the FIG. 1 embodiment; and,

FIG. 4 is a side view of a battery in accordance with the FIG. 1 embodiment.
